UNITED STATES PATENT OFFICE.

ROBERT D. JAMISON, OF DETROIT, MICHIGAN.

DESIGN FOR A LAMP-CHIMNEY.

SPECIFICATION forming part of Design No. 35,723, dated February 11, 1902.

Application filed November 18, 1901. Serial No. 82,786. Term of patent 14 years.

To all whom it may concern:

Be it known that I, ROBERT D. JAMISON, a citizen of the United States, residing at Detroit, county of Wayne, State of Michigan, have invented and produced a new and original Design for a Lamp-Chimney, of which the following is a specification, reference being had to the accompanying drawings, which form a part of this specification.

10 In the drawings, Figure 1 is a view in perspective, illustrating my new design. Fig. 2 is a view in vertical section.

As shown herewith, the body of a lamp-chimney is shown at *a*, and *b* is the base of the chimney, said base consisting of an outwardly-projecting bead *c*, provided with a series of indentations or corrugations *d* on

the under side thereof. The under side of the bead is upwardly and outwardly inclined, as shown, the surfaces of the bead converging toward its periphery and the outer periphery projecting outward beyond the corrugations on the under surface thereof.

Having described my invention, what I claim as new, and desire to secure by Letters Patent, is—

The design for a lamp-chimney as herein shown and described.

In testimony whereof I sign this specification in the presence of two witnesses.

ROBERT D. JAMISON.

Witnesses:

N. S. WRIGHT,
J. M. POLAND.
